(57) **CLAIM**

The ornamental design for a water basin, as shown and described.

DESCRIPTION

FIG. 1 is an exploded top perspective view of a water basin, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of a water basin;

FIG. 10 is a rear perspective view thereof;

FIG. 11 is an enlarged detail view of area 11 in FIG. 1;

FIG. 12 is an enlarged detail view of area 12 in FIG. 1;

FIG. 13 is an enlarged detail view of area 13 in FIG. 1;

FIG. 14 is an enlarged detail view of area 14 in FIG. 1;

FIG. 15 is an enlarged detail view of area 15 in FIG. 1; and,

FIG. 16 is an enlarged detail view of area 16 in FIG. 6.

The broken lines in the drawings illustrate portions of the water basin, which form no part of the claimed design.

The dash-dot-dash broken lines in FIGS. 1 & 11-16 depict the boundary of the enlargement area and form no part of the claimed design.
